STEAM GENERATOR

Walter Gustav Noack, Baden, Switzerland, assignor to Aktiengesellschaft Brown Boveri & Cie., Baden, Switzerland, a joint-stock company of Switzerland

Application August 20, 1931, Serial No. 558,262,
and in Germany September 1, 1930. Renewed
October 14, 1933

11 Claims. (Cl. 122—511)

This application is a continuation in part of my copending applications Serial No. 343,745, filed March 1, 1929 and Serial No. 375,138, filed July 1, 1929.

5 The present invention relates to steam generators of the type in which a combustible mixture is subjected to combustion under pressure in a combustion chamber, and the pressure is utilized to impart to the hot combustion gases a velocity 10 of the order of about 200 meters per second or more at which the compressibility of the gases becomes effective through the inlets of a set of gas tubes of a heat exchanger passing a steam generating fluid around the tubes for generating steam 15 therein. The present invention provides an improved arrangement of the gas tubes in such steam generator which greatly reduces the pressure needed for discharging the gases at the required high velocity.

20 The objects of the invention will be best understood from the following description of exemplifications thereof, reference being had to the accompanying drawings, wherein

Fig. 1 is a diagrammatic view of a steam generator with a combustion chamber made in accordance with the invention; and

Figs. 2, 3 and 4 are detailed sectional views of different modifications of the gas discharge tubes embodying the invention.

30 In Fig. 1 is illustrated a steam generator of the type illustrated in my copending prior applications Serial No. 343,746, filed March 1, 1929 and Serial No. 414,428, filed December 16, 1929, in which an extremely high rate of steam generation 35 is secured by subjecting a combustible charge to combustion under pressure in a pressure-proof chamber and utilizing the pressure of the hot combustion gases formed in the chamber for imparting to said gases a very high velocity through 40 a set of gas tubes traversed on the outside by a steam generating fluid, such as water, thereby securing a very high rate of heat transference from the hot gases to the water and, as a consequence, very large steam generation within a 45 relatively small structure.

The steam generator comprises a pressure-proof combustion chamber 1 having a main cylindrical section 2 with an inlet header 3 enclosing the bottom and an outlet header 4 enclosing the top of the chamber. Within the walls 50 of the inlet header 3 is formed a water inlet chamber 5 and within the walls of the outlet header 4 is formed a water outlet chamber 6. A set of water tubes 7 is mounted along the periphery of the chamber 1 forming the inner walls

thereof, the tubes being surrounded by a cylindrical outer wall 8. The tubes 7 are connected between the water inlet chamber 5 and the water outlet chamber 6 to pass water that is heated and vaporized while passing through the tubes, the 80 mixture of hot water and steam being discharged through a conduit 10 into a steam separator 11, the steam separating and collecting in the upper part of the separator from where it is supplied to the load, and the water being collected in the 85 lower part of the separator, fresh feed water being supplied thereto through pipe 12. The water from the separator 11 is circulated through water tubes 7 by means of water pump 13 which is connected by pipes 14 between the separator 11 and 70 inlet 15 of water chamber 5.

A combustible charge, such as a gas or air with fuel admixed thereto, is compressed by compressor 20 and delivered to combustion chamber 1 through conduit 21 and a suitable inlet 22. The 75 admitted compressed combustible charge is subjected to combustion in the chamber. The pressure of the hot combustion gases is utilized to drive the gases at a velocity of about 200 meters per second or above through a set of gas or fire 80 tubes 26 connected to the upper end of the chamber and leading through the interior of the water tubes 7, the gases being discharged into the gas outlet duct 27, and therefrom, through pipe 28 85 into a gas turbine where a part of the energy still remaining in the gases is applied to drive compressor 20 and thus serves to initially compress the combustible charge supplied to the chamber. Additional driving power may be supplied to the compressor by an auxiliary motor 30, such as a 90 steam engine or Diesel engine, coupled to the gas turbine 29, the total power supplied by the motor and the turbine being proportioned to be sufficient to produce in the compressor the pressure head necessary for imparting to the combustion 95 gases the high velocity and for driving the auxiliary gas turbine to supply a part or all of the initial charging pressure.

The combustion within the chamber 1 may be carried on either as a continuous process, in which 100 case the inlet 12 forms a burner at which a continuously supplied compressed charge is continuously burned within the chamber; or, the combustion may be carried on as a periodical process like in a combustion engine, in which case the inlet 12 is arranged as a valve which periodically opens and admits an initially compressed charge which is then exploded in the chamber, as by spark plugs mounted within the chamber, the process being cyclically repeated and the pres- 110

sure of the generated hot combustion gases imparting to them the high velocity through the gas tubes 26. Considerable pressure drops must be available in the gases within the chamber in order 5 to produce the high flow velocities of the gases through the gas tubes. For reasons of economy it is important that this pressure drop shall be as low as possible.

In accordance with the present invention, production of high gas velocities through gas tubes with small pressure drops is made possible by provision of nozzles 32 at the inlets of the gases into the gas tubes 26 and of diffusers 33 at the outlets, as shown in Fig. 1, and with more detail in Fig. 2. The nozzle 32 is so shaped that the pressure efficiently imparts to the combustion gases the high velocity already at the entrance into the tube 26, that is, at the place where the combustion gases are still at the maximum temperature, so that relatively small differences in pressure will already suffice for producing considerable heat drops and consequently high velocities of flow. In just the opposite way, the outlet end of the gas tube terminates into a widening diffuser 33 in which the still high velocity of the gases is reconverted into pressure. Since the gases passing the end portion of the gas tube are already considerably cooled down, and have greater density, they can, at a given velocity of flow, overcome a greater pressure ratio in the diffuser than that which was required to impart such velocity to the hot gases in the nozzle. By cooling the gases in the gas tubes and generating steam with the heat derived from the gases, it would thus be theoretically possible to produce with the diffuser, without any external compression work, not only the pressure drop required for producing the high velocity gas flow, but even a certain excess pressure. This is not fully the case in practice, because the compression work in the diffuser is effected with a far lower degree of efficiency than the imparting of the velocity in the nozzle, and also because, notwithstanding the rate of heat exchange obtained, the transfer 40 of the heat from the gases to the fluid around the tubes requires a tube length at which the tube resistance becomes appreciable. The provision of a nozzle at the inlet and a diffuser at the outlet of the gas tubes as described above makes possible a very considerable reduction of the pressure difference required to produce the high velocity gas flow, and thus enables reduction of the compressor work for initial compression of the charge. With regard to the amount of the tube 45 resistance, consideration is also to be given to the fact, that the diminution in velocity caused by the cooling of the gases likewise results in a recompression effect like that produced in the diffuser, this recompression being equivalent to a reduction of the tube resistance.

The fire tubes of the steam generators made in accordance with the invention may have different forms. In the construction shown in Figs. 1 and 2, the fire tube 26 is throughout its length of uniform cross section, for instance, cylindrical in shape, with the nozzle 32 at the inlet to efficiently impart to the hot combustion gases their full velocity at the entrance in the tube, and a diffuser at the outlet for reconverting the velocity of the outflowing gases into a pressure head which assists in imparting the high velocity to the gases and reduces the amount of pressure that must initially be imparted to the charge. Because of the uniform cross section of the tube, the velocity of the flowing gas decreases

to some extent along the tube, in accordance with the decrease of the absolute temperature of the gases in the tube.

In the construction shown in Fig. 3, the fire tube 35 decreases in cross section in the direction of gas flow, being also provided with a nozzle 36 and a diffuser 37 like that of Fig. 2. The diminution in cross section may be proportioned to cause the velocity to remain constant throughout the length of the tube from the nozzle till the narrowest point at the junction with the diffuser 37. The diminution of the cross section may be obtained in a simple way by flattening a circular tube to make it increasingly oval towards the outlet end.

In Fig. 4 is shown a fire tube 38 which is, as a whole, constructed as a diffuser, the tube gradually increasing in cross section from the point where it joins the nozzle 39 at its inlet, and acting as the heating surface for transmitting the heat of the gases to the surrounding water.

The fire tubes are preferably made as nearly straight as possible. Only the velocity of the gas is slowed down and converted into pressure within the diffuser, and solid particles, such as ashes, flowing with the gas do not take part in the change in velocity. This feature is utilized for separating ash and clinker from the gases discharged through the fire tubes. To this end the diffuser ends are arranged in the gas outlet duct 27, as shown in Figs. 1 and 2, to permit lateral outflow of the slowed down gases, diverting the relatively high velocity ash and clinker particles from the gas, and collecting them in a space at the bottom of the gas duct 27.

The high velocity gas flow at reduced combustion chamber pressure is maintained by the pressure gain in the diffuser only as long as the diffuser operates correctly. As in case of other devices which operate according to similar dynamic laws, the gas flow through the diffuser may become interrupted and the vacuum destroyed. In order to keep the fire tube in proper operating condition notwithstanding such interruption, means are provided for regulating the pressure ratio in the nozzle 32 or in the diffuser 33 by influencing the control of the motor 30 which drives the compressor 20 in accordance with the pressure of the gases after the nozzle or before the diffuser. This is shown in Fig. 1, where a pressure-responsive device 34 mounted on the fire tube 26, before the diffuser 33, regulates through line 35 the admission of driving energy, such as steam or fuel, to the auxiliary compressor motor 30 to speed up the compressor and increase its pressure if the pressure ratio in the diffuser diminishes. In this way, an interruption of the gas discharge in the tubes, or a decrease of its velocity, will immediately produce an increase of the chamber pressure, increasing the gas velocity and the pressure ratio in the nozzle and diffuser. On restoration of the correct working conditions, the speed of the compressor set is automatically brought back to normal.

Many other modifications of the invention will suggest themselves to those skilled in the art and I desire, accordingly, that the appended claims be given a broad construction commensurate with its scope in the art.

I claim:

1. The combination with a steam generator comprising a pressure-proof combustion chamber, and means for supplying a combustible charge to said chamber and for subjecting said charge to combustion within said chamber to

- produce hot combustion gases of a pressure higher than the external pressure, of a heat exchanger having a plurality of gas tubes connected to said chamber and arranged to cause the pressure within the chamber to impart to the hot combustion gases a velocity of about 200 meters per second or more through nozzle-like entrances into said tubes, tubular enclosure means surrounding said tubes for passing a steam generating fluid at a pressure higher than the external pressure, the inlet ends of said tubes having nozzle-like constrictions to impart to the combustion gases said high velocity at the entrance into the tubes, and the outlet ends of said tubes being diffuser-like enlarged, increasing in cross section in the direction of the gas flow to slow down the outflowing gases and utilize their velocity for increasing the pressure at the outlet ends of the tubes above the pressure value in the portions lying back of the outlet points. 10
2. The combination with a steam generator comprising a pressure-proof combustion chamber, and means for supplying a combustible charge to said chamber and for subjecting said charge to combustion within said chamber to produce hot combustion gases of a pressure higher than the external pressure, of a heat exchanger having a plurality of gas tubes connected to said chamber and arranged to cause the pressure within the chamber to impart to the hot combustion gases a velocity of about 200 meters per second or more through nozzle-like entrances into said tubes, tubular enclosure means surrounding said tubes for passing a steam generating fluid at a pressure higher than the external pressure, constricted nozzles at the inlet ends of said tubes to impart to the combustion gases said high velocity at the entrance into the tubes, and divergent diffusers at the outlets of said tubes increasing in cross section in the direction of the gas flow for slowing down the outflowing gases and building up a pressure assisting in imparting the high velocity at the inlet side of the tubes. 20
3. The combination with a steam generator comprising a pressure-proof combustion chamber, and means for supplying a combustible charge to said chamber and for subjecting said charge to combustion within said chamber to produce hot combustion gases of a pressure higher than the external pressure, of a heat exchanger having a plurality of gas tubes connected to said chamber and arranged to cause the pressure within the chamber to impart to the hot combustion gases a velocity of about 200 meters per second or more through nozzle-like entrances into said tubes, tubular enclosure means surrounding said tubes for passing a steam generating fluid at a pressure higher than the external pressure, constricted nozzles at the inlet ends of said tubes to impart to the combustion gases said high velocity at the entrance into the tubes, and divergent diffusers at the outlets of said tubes increasing in cross section in the direction of the gas flow for slowing down the outflowing gases and building up a pressure assisting in imparting the high velocity at the inlet sides of the tubes, the tube portions lying between the nozzles and the diffusers, decreasing in cross section in the direction of the gas flow. 30
4. The combination with a steam generator comprising a pressure-proof combustion chamber, and means for supplying a combustible charge to said chamber and for subjecting said charge to combustion within said chamber to produce hot combustion gases of a pressure higher than the external pressure, of a heat exchanger having a plurality of gas tubes connected to said chamber and arranged to cause the pressure within the chamber to impart to the hot combustion gases a velocity of about 200 meters per second or more through nozzle-like entrances into said tubes, tubular enclosure means surrounding said tubes for passing a steam generating fluid at a pressure higher than the external pressure, and constricted nozzles at the inlet ends of said tubes to impart to the combustion gases said high velocity at the entrance into the tubes, said tubes being of divergent diffuser-like shape, increasing in cross section in the direction of the gas flow. 40
5. The combination with a steam generator comprising a pressure-proof combustion chamber, and means for supplying an initially compressed combustible charge to said chamber and for subjecting said charge to combustion within said chamber to produce hot combustion gases of a pressure higher than the external pressure, of a heat exchanger having a plurality of gas tubes connected to said chamber and arranged to cause the pressure within the chamber to impart to the hot combustion gases a velocity of about 200 meters per second or more through nozzle-like entrances into said tubes, tubular enclosure means surrounding said tubes for passing a steam generating fluid at a pressure higher than the external pressure, the inlet ends of said tubes having nozzle-like constrictions to impart to the combustion gases said high velocity at the entrance into the tubes, the outlet ends of said tubes being diffuser-like enlarged, increasing in cross section in the direction of the gas flow to slow down the outflowing gases and utilize their velocity for increasing the pressure at the outlet ends of the tubes above the pressure value in the portions lying back of the outlet points, and means responsive to the pressure conditions of the gas in the tube for controlling the initial compression of the charge supplied to said chamber. 50
6. The combination with a steam generator comprising a pressure-proof combustion chamber, means including a compressor for supplying an initially compressed combustible charge to said chamber and for subjecting said charge to combustion within said chamber to produce hot combustion gases of a pressure higher than the external pressure, and a motor for driving said compressor, of a heat exchanger having a plurality of gas tubes connected to said chamber and arranged to cause the pressure within the chamber to impart to the hot combustion gases a velocity of about 200 meters per second or more through nozzle-like entrances into said tubes, tubular enclosure means surrounding said tubes for passing a steam generating fluid at a pressure higher than the external pressure, the inlet ends of said tubes having nozzle-like constrictions to impart to the combustion gases said higher velocity at the entrance into the tubes, the outlet ends of said tubes being diffuser-like enlarged, increasing in cross section in the direction of the gas flow to slow down the outflowing gases and utilize their velocity for increasing the pressure at the outlet ends of the tubes above the pressure value in the portions lying back of the outlet points, and means responsive to the pressure conditions of the gas in an end portion of a tube for increasing the compression of the 60

charge supplied to the combustion chamber in response to decrease of the tube gas velocity.

7. A steam generator comprising a pressure-proof combustion chamber, means for supplying a combustible charge to said chamber and for subjecting said charge to combustion within said chamber to produce hot combustion gases of a pressure higher than the external pressure, said hot combustion gases including light solid particles, a heat exchanger having a plurality of gas tubes connected to said chamber and arranged to cause the pressure within the chamber to impart to the hot combustion gases and the solid particles carried therein a velocity of about 200 meters per second or more through nozzle-like entrances into said tubes, tubular enclosure means surrounding said tubes for passing a steam generating fluid at a pressure higher than the external pressure, and means at the outlet ends of said tubes for slowing down the velocity of the outflowing gases while maintaining relatively high velocity of the solid particles moving with the gas to separate the solid particles from said outflowing gases.
- 25 8. A steam generator comprising a pressure-proof combustion chamber, means for supplying a combustible charge to said chamber and for subjecting said charge to combustion within said chamber to produce hot combustion gases of a pressure higher than the external pressure, said hot combustion gases including light solid particles, a heat exchanger having a plurality of gas tubes connected to said chamber and arranged to cause the pressure within the chamber to impart to the hot combustion gases and the solid particles carried therein a velocity of about 200 meters per second or more through nozzle-like entrances into said tubes, tubular enclosure means surrounding said tubes for passing a steam generating fluid at a pressure higher than the external pressure, said tubes having divergent diffuser-like outlets, increasing in cross section in the direction of the gas flow to slow down the outflowing gases while permitting retainer of substantially higher velocity by the solid particles present in the outflowing gases, and means at the outlet ends of said tubes for diverting the slowed down outflowing gases from the path of the outflowing high velocity solid particles to separate the same from the gas.
- 35 9. The method of generating steam for supplying a steam consuming load, which comprises initially compressing a gaseous body and forming therewith a combustible charge of a substantial raised pressure, subjecting said charge to combustion under pressure within a pressure-proof combustion chamber, applying the pressure within said chamber for imparting to the combustion gases at nozzle-like entrances of a

set of heat exchanger tubes a velocity of about 200 meters per second or more through said tubes, passing a steam generating fluid around said tubes to absorb heat from the gases and generate steam, and applying the velocity of the combustion gases passing through said tubes, in diffuser-like outlet portions thereof, to recompress the outflowing gases and supply in the outlet portions of said tubes a part of the pressure drop for imparting to the gases the initial velocity at said nozzle-like tube entrances.

10. A vapor generator comprising a pressure-proof combustion chamber, means for supplying a combustible charge to said chamber and for subjecting said charge to combustion within said chamber to produce hot combustion gases of a pressure higher than the external pressure, heat exchange means holding a vaporizable liquid and having a set of heating tubes connected to said chamber for discharging the hot combustion gases from said chamber, the chamber inlet ends of said tubes having constricted inlet nozzles constructed and proportioned to apply the pressure of the gases for driving the hot gases from said chamber through said inlet nozzles into the tubes at a velocity of the order of about 200 meters per second or more to heat said liquid and generate steam, and the outlet ends of said tubes being diffuser-like enlarged, increasing in cross section in the direction of the gas flow to slow down the outflowing gases and utilize their velocity for increasing the pressure at the outlet ends of the tubes above the pressure value in the portions lying back of the outlet points.

11. A vapor generator comprising a pressure-proof combustion chamber, means for supplying a combustible charge to said chamber and for subjecting said charge to combustion within said chamber to produce hot combustion gases of a pressure higher than the external pressure, heat exchange means holding a vaporizable liquid and having a set of heating tubes connected to said chamber for discharging the hot combustion gases from said chamber, the chamber inlet ends of said tubes having constricted inlet nozzles constructed and proportioned to apply the pressure of the gases for driving the hot gases from said chamber through said inlet nozzles into the tubes at a high velocity above 100 meters per second or more to heat said liquid and generate steam, and the outlet ends of said tubes being diffuser-like enlarged, increasing in cross section in the direction of the gas flow to slow down the outflowing gases and utilize their velocity for increasing the pressure at the outlet ends of the tubes above the pressure value in the portions lying back of the outlet points.
